Primary Examiner — Elizabeth J Oswecki(74) *Attorney, Agent, or Firm* — Hamre, Schumann, Mueller & Larson, P.C.(57) **CLAIM**

The ornamental design for a support for a probe test core, as shown and described.

DESCRIPTION

FIG. 1 is a perspective view of a support for a probe test core showing our new design, with a probe test core shown in broken lines for environment that forms no part of the claimed design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.
